[57] CLAIM

The ornamental design for a bathroom counter top, as shown and described.

DESCRIPTION

FIG. 1 is a top perspective view of a bathroom counter top showing my new design;
FIG. 2 is a top plan view thereof;
FIG. 3 is a front elevational view thereof;
FIG. 4 is a right side elevational view thereof;
FIG. 5 is a left side elevational view thereof;
FIG. 6 is a rear elevational view thereof;
FIG. 7 is a bottom plan view thereof;
FIG. 8 is a top perspective view of a second embodiment thereof;
FIG. 9 is a top plan view of FIG. 8;
FIG. 10 is a front elevational view of FIG. 8;
FIG. 11 is a right side elevational view of FIG. 9;
FIG. 12 is a left side elevational view of FIG. 8;
FIG. 13 is a top perspective view of a third embodiment thereof;
FIG. 14 is a top plan view of FIG. 13;
FIG. 15 is a front elevational view of FIG. 13;
FIG. 16 is a right side elevational view of FIG. 13;
FIG. 17 is a left side elevational view of FIG. 13;
FIG. 18 is a top perspective view of a forth embodiment thereof;
FIG. 19 is a top plan view of FIG. 18;
FIG. 20 is a front elevational view of FIG. 18;
FIG. 21 is a right side elevational view of FIG. 18;
FIG. 22 is a left side elevational view of FIG. 18;
FIG. 23 is a rear elevational view of FIG. 18;
FIG. 24 is a bottom plan view of FIG. 18;
FIG. 25 is another top perspective view of FIG. 18, showing a single sink opening; and,
FIG. 26 is a third top perspective view of FIG. 18, showing two sink openings.

The broken line representations of sink openings in FIGS. 1, 2, 7, 8, 9, 13, 14, 25 and 26 and of fitting openings in FIG. 25 are for purposes of illustration only and form no part of the claimed design.
